DESIGN FOR A DISPENSER FOR FACE CREAM OR THE LIKE

Robert Gordon Bau, North Hollywood, Calif.

Application September 10, 1948, Serial No. 148,548

Term of patent 14 years

(Cl. D86—10)

To all whom it may concern:

Be it known that I, Robert Gordon Bau, a citizen of the United States, residing at North Hollywood, in the county of Los Angeles and State of California, have invented a new, original, and ornamental Design for a Dispenser for Face Cream or the like, of which the following is a specification, reference being had to the accompanying drawing, forming part thereof.

Fig. 1 is a front view in elevation of a dispenser for face cream or the like, showing my new design.

Fig. 2 is a side view in elevation.

Fig. 3 is a top plan view.

I claim:

The ornamental design for a dispenser for face cream or the like, substantially as shown.

ROBERT GORDON BAU.
